Filed Dec. 18, 1964, Ser. No. 419,371
10 Claims. (Cl. 242—45)

ABSTRACT OF THE DISCLOSURE

A machine for re-spooling wire by simultaneously rotating and axially reciprocating the spindle on which a spool is mounted, tension of the wire being maintained substantially constant by regulating the torque transmitted to the spindle and the speed with which the spindle is reciprocated. The torque transmitted is regulated by both slippage in a slip clutch through which power is transmitted to the spindle and the reciprocating mechanism and the drag imposed by a brake through which power is absorbed.

This invention relates to a machine for re-spooling wire or the like and more particularly to a heavy-duty power transmitting device through which a winding spool or drum may be continuously rotated and axially reciprocated in order to wind wire thereon under a constant tension.

One of the major achievements of the present invention is the provision of a machine through which a relatively large spool or winding drum for wire may be rotated at a relatively high speed and yet wind the wire thereon with a substantially constant tension the driven spool also being cyclically reciprocated at it is continuously rotated in order to axially distribute the wire being wound thereon.

It is generally known that electromagnetically operated devices may be employed for torque controlling purposes in a winding operation in an attempt to regulate wire tension.

When dealing with relatively large wire winding spools that are reciprocated, there is a considerable problem involved in maintaining constant wire tension and imparting reciprocation to the driven member while it is being rotated at a relatively high speed because of the high accelerating forces involved and their effect on the transmission parts. Because of the arrangement of parts and the design of the components which form the machine of the present invention, the foregoing problems have been successfully dealt with.

It is therefore an important object of the present invention to provide a transmission through which power from a constant source of motive power is controllably supplied to a driven spindle at a speed varied in order to maintain a constant torque on the load to which the spindle is connected, which load is continuously varied as would be the case when wire is being wound upon a spool to which the spindle is connected.

In accordance with the foregoing object, an additional object of the present invention is to provide a slip clutch and drag brake assembly through which power is transmitted and absorbed to control the power delivered to the driven spindle member. The relative slipping of the coupling clutch and drag brake is automatically controlled utilizing in a novel arrangement, magnetic means of a type which automatically adjusts for changes in flux gap due to wear.

A still further object of the present invention is to provide a power transmitting train through which continuous rotation as well as axial reciprocation is imparted to a driven spindle member at relatively high speeds.

2

An additional object of the present invention is to provide a reciprocating drive mechanism associated with a continuously rotated driven spindle capable of coping with the high accelerating forces involved.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the machine of the present invention.

FIGURE 2 is a perspective view of the machine as viewed from another angle.

FIGURE 3 is a top sectional view of the machine shown in FIGURES 1 and 2.

FIGURE 4 is a sectional view taken substantially through a plane indicated by section line 4—4 in FIGURE 3.

FIGURE 5 is a sectional view taken substantially through a plane indicated by section line 5—5 in FIGURE 4.

FIGURE 6 is a rear elevational view of the machine shown in FIGURES 1 and 2.

FIGURE 7 is a simplified perspective view of the drive train associated with the machine.

FIGURE 8 is an enlarged partial sectional view of a portion of the machine as illustrated in FIGURE 4.

FIGURE 9 is a partial sectional view taken substantially through a plane indicated by section line 9—9 in FIGURE 8.

FIGURE 10 is a partial sectional view taken substantially through a plane indicated by section line 10—10 in FIGURE 9.

FIGURE 11 is an enlarged partial sectional view of a portion of the machine illustrated in FIGURE 5.

FIGURE 12 is a partial sectional view taken substantially through a plane indicated by section line 12—12 in FIGURE 11.

Referring initially to FIGURES 1, 2 and 6, it will be observed that the machine generally referred to by reference numeral 10, includes a housing frame assembly generally referred to by reference numeral 12 adjustably positioned on a supporting surface or floor by means of a track frame assembly generally referred to by reference numeral 14. The housing frame assembly 12 includes four vertical frame posts 16 interconnected at the lower ends, by a supporting platform 18 and by horizontal frame members 20 at the upper ends. Also, interconnecting the vertical posts 16 intermediate the upper and lower ends thereof, is a second supporting platform 22 on which there is carried a reciprocating drive mechanism generally referred to by reference numeral 24 as well as a pair of slide journal assemblies 26 and 28 by means of which an output spindle member 30 is supported for continuous rotation and axial reciprocation. The spindle 30 is adapted to be connected to a wire winding spool 32 as shown by dotted lines in FIGURES 1 and 2. Power for driving the spindle 30 is derived from an electric gear motor assembly 34 mounted in fixed position on the base platform 18. The base platform also supports power transmitting facilities through which the power is transmitted to the spindle 30 for continuous rotation thereof as well as to the reciprocating drive mechanism 24.

In order to adjustably position the housing frame assembly 12 and the driven spindle 30 projecting forwardly therefrom, each of the vertical posts 16 have connected to the lower ends thereof, supporting wheel assemblies 36 guided for movement along a pair of parallel spaced track portions 38 which extend upwardly from the positioning track assembly 14. A positioning screw 40 is therefore rotatably mounted adjacent one end, by a supporting

journal bracket 42 fixedly mounted on the forward end of the track assembly. The positioning screw is threadedly received through a nut assembly 44 mounted on the platform 18. Accordingly, the housing frame assembly 12 may be displaced along the track portions 38 by rotation of the screw member through the hand crank 46 between limits established by the limiting nuts 48 and 50. Once the housing frame assembly has been positioned to the desired location, it may be fastened to the floor by means of bolts extending through the anchoring flanges 52 secured to the opposite sides of the base platform 18 adjacent the track portions 38.

After the housing frame assembly has been locked in adjusted position to properly align the driven spindle 30 and the wire winding spool 32 mounted thereon, with the source of wire, depending upon the size and shape of the winding spool, its reciprocating speed may be adjusted through the adjusting handwheel 54 which projects forwardly from the housing assembly while the reciprocating stroke may be adjusted by means of the stroke adjusting handwheel 56 which projects laterally from the side of the housing assembly as shown in FIGURE 1. An endless belt drive 58 transmits the power from the gear motor assembly 34 to both the driven spindle 30 for rotation thereof and to the reciprocating drive mechanism 24 adjusted by means of the handwheels 54 and 56. Toward this latter end, an endless belt drive 60 is mounted rearwardly of the housing assembly as shown in FIGURE 6 for transmitting power to the driven spindle connected to the driven pulley 62 for continuous rotation thereof. A drive pulley 64 is driven by the power transmitting facilities so as to impart continuous rotation through the belt drive 60 to the driven spindle 30. A second belt drive 66 having a belt tightener 68, is also disposed rearwardly of the housing assembly drivingly interconnecting the drive pulley 70 with the driven pulley 72 in order to supply power at a reduced speed to the reciprocating drive mechanism.

Referring now to FIGURE 7, it will be observed that the endless drive belt 58 transmits power from the electric gear motor assembly 34 to an intermediate power shaft 74 to which the driven pulley 64 is connected so as to transmit continuous rotation to the driven spindle 30 by means of the belt drive 60. Also connected to the power shaft 74, is a drive pulley 76 drivingly connected by means of the endless belt drive 78 to a driven pulley 80 connected to the input shaft 82 of a ten to one reduction drive assembly 84 of a conventional type. The reduction ratio of the reduction drive assembly 84 may therefore be varied through the ratio adjusting handwheel 54 aforementioned in order to control the speed of the drive pulley 70. The drive pulley 70 thereby imparts rotation to the cam shaft 86 associated with a reciprocating drive assembly 24 at a regulated reduction drive ratio through the endless belt drive 66. The reciprocating drive mechanism 24 is thereby operative to impart reciprocation to the driven spindle 30 as it is being continuously rotated.

Referring now to FIGURES 3, 4 and 5 in particular, it will be observed that the cam shaft 86 is rotatably mounted above the upper platform 22 between the journal assemblies 88 and 90, the cam shaft projecting rearwardly beyond the journal assembly 90 for connection to the driven pulley 72 as aforementioned. The cam shaft is provided with a pair of spiral grooves 92 and 94 having helix angles inclined in opposite directions so as to cause linear movement of a reciprocating follower device 96 in response to uni-directional rotation imparted to the cam shaft. The reciprocating speed of the reciprocating drive mechanism will thereby be governed by the speed of the driven pulley 72, this speed in turn being regulated through the variable speed, reduction drive assembly 84 aforementioned. Although the stroke of the follower drive 96 is fixed along the cam shaft 86, the reciprocating stroke imparted to the spindle 30 may be varied by the adjustable positioning of a fulcrum block 98 which pivotally mounts

a lever rod 100. Accordingly, the lever rod 100 is pivotally connected by the yoke 102 at one end to the follower device 96 and at the opposite end it is operatively connected by the pivotal slide yoke 104 to a bearing sleeve member 106 through which the spindle 30 extends. The sleeve member 106 is therefore axially positioned on the spindle 30 between a pair of collar members 108 through which axial thrust is transmitted to the spindle. Each of the journal assemblies 24 and 26 therefore include roller bearings 110 and slide bearings 112 through which the spindle 30 extends. The sleeve member 106 through which axial movement is imparted to the spindle, has a pair of pivot elements 114 extending through slots 116 in the yoke member 104 to which the lever rod 100 is connected. Accordingly, as the lever rod 100 is oscillated about a vertical axis established through the fulcrum block 98, by means of the reciprocating follower device 96, axial reciprocation will be imparted to the spindle 30. By controlling the position of the fulcrum block 98, the reciprocation ratio and hence the stroke of the spindle 30 may be regulated. The stroke adjusting handwheel 56 is therefore connected to a positioning screw member 118 rotatably mounted above the platform 22 by the bearings 120 and the slide adjusting bracket 122. A nut member 124 is threadedly mounted on the screw adjustment member 118 for slidable displacement along the adjustment screw 118 when rotated by the handwheel 56. The adjustment nut 124 is pivotally connected by the pivot connection 126 to the fulcrum block 98 through which the lever rod 100 slidably extends. Accordingly, the fulcrum block 98 may be slidably positioned so as to establish a pivotal axis through the pivot connection 126 aligned with the pivot connection 128 through which the fulcrum block is also guided for positioning movement by a top guide member 130 as shown in FIGURE 5.

Referring now to FIGURES 5, 11 and 12, it will be observed that the lever rod 100 is pivotally connected by the yoke member 102 to the follower device by means of a pair of pivot connections 132 establishing a pivotal axis 40 which intersects the axis of the cam shaft 86. The follower device includes a slide block 134 threadedly receiving the pivotal connecting elements 132 and also being provided with a bore 136 through which the cam shaft 86 extends. Also formed in the block 134, is a laterally extending bore 138 which intersects the bore 136. A groove engaging element 140 is rotatably mounted within the bore 138 about a pivotal axis established by the threaded stud 142 projecting inwardly from the cover plate 144 secured by fasteners 146 to the block 134. The groove engaging element is provided with an arcuate tooth portion 148 having a radius of curvature as shown in FIGURE 11, corresponding to the root diameter of the cam shaft 86 so that the tooth portion may be received within the spiral groove 92 and 94 without interference. The tooth portion 148 also tapers inwardly in non-radial relation to the cam shaft 50 and has a maximum thickness at the pivotal axis established through the stud 142 as more clearly seen in FIGURE 12. In this manner, the axial direction of the follower device may be reversed at the end of its stroke by pivotal displacement of the follower element 140 about its pivotal axis, transferring the tooth portion 148 from one spiral groove to the other without interference.

Referring now to FIGURES 4 and 5, it will be observed that the belt drive 58 drivingly connects the drive pulley 150 to a driven pulley 152, the drive pulley being connected 65 to the output shaft 154 of the gear motor assembly 34 from which a constant source of power is derived. The driven pulley 152 is rotatably mounted on the intermediate power shaft 74 rotatably supported by the journal bearing assemblies 156, 212 and 158. The assembly 156 is supported in proper position by the suspension plate 160 secured to the platform 22 while the rearward journal assemblies 212 and 158 are supported in proper position by means of the hanger structures 210 and 162 projecting 70 downwardly from the platform 22 as shown in FIGURE

4. The driven pulley 152 is secured to a drive member 164 supported for rotation on the forward portion 165 of power shaft 74. The power shaft 74 is provided with spaced splined portions 166, 168 and 170 for rotatively connecting the power shaft to a slip clutch and brake assembly 172, and to the drive pulley wheels 76 and 64 aforementioned. The slip clutch and brake assembly 172 is thereby operative to regulate the power transmitted to the drive pulleys 76 and 64 for the purposes of the present invention.

Referring now to FIGURES 8, 9 and 10 in particular, it will be observed that the drive member 164 is associated with a clutch and brake assembly 172 including a slip coupling clutch unit 173 supported for rotation on the power shaft 74 by the drive member 164 having spaced needle bearings 174 lubricated by lubricant supplied through the bore 176. The drive member is also held in axially fixed position on portion 165 of the power shaft by means of the bearing assembly 156 separated from one axial end of the drive member by the thrust washer 178, the opposite axial end of the drive member abutting a second thrust washer 180 which is seated against the shoulder 182 formed on the power shaft. The drive member includes an externally splined portion 183 axially spaced from the driven pulley member 152 for mounting a clutch armature disk 184. The clutch disk carries therewith a plurality of circumferentially spaced magnetic flux conducting elements 186 and is spaced by a small flux gap from the forward axial face 188 of a torque absorbing clutch member 190 when disengaged. The clutch disk 184 is provided with a plurality of circumferentially spaced spring elements 192 which project radially inwardly into engagement with the drive member. Thus, the clutch disk 184 is magnetically attracted to and held in engagement with the slip clutch member 190 against the spring bias of the spring elements 192 through the magnetic elements 186 by electromagnetic means (not shown). In this manner, a continuous axial bias will be imposed on the slip clutch member when transmitting torque to yieldably hold it in frictional engagement with a driven conical member 194. The driven conical member 194 is therefore splined to the power shaft 74 along the spline portion 166 and is limited in axial displacement in one direction by the thrust washer 180. The axial bias imposed on the slip clutch member therefore causes it to engage the driven member while permitting slippage when transmitting rotation to the power shaft. Because of the foregoing arrangement any change in the flux gap resulting from slippage wear will be compensated for by advancement of the faces on the disc 184 toward the clutch member 190. This type of flux gap compensating feature is embodied in clutch and brake units identified as "Dyna-Torq" spline drive Model 312, manufactured by Dynamatic Division of Eaton Manufacturing Co., of Kenosha, Wisconsin, as shown in its bulletin dated May 31, 1962, also described in its pamphlet "Eaton Dyna-Torq Stationary Field Clutches and Clutch-Couplings," the details of which form no part of the present invention. A bearing sleeve element 200 is received within the socket 196 of the clutch member forming a radially inner bearing race for the ball elements 195 and axially spacing the conical drive member 194 from a second conical driven member 202 associated with a drag brake unit 204.

The drag brake unit is similar in construction and operation to the slip clutch unit 173 and includes a stationary, torque absorbing brake member 206 through which power is absorbed in order to reduce and stop transmission of power through the power shaft to the driven spindle and the reciprocating drive mechanism. The brake member 206 may therefore be fixed in any suitable fashion to a plate 208 which in turn may be secured to the hanger structure 210 suspending the bearing assembly 212. The brake member 206 is made of magnetic material similar to the slip clutch member 190 and is similarly spaced by a flux gap from circumferentially spaced magnetic elements 214 carried by a brake disk 216. The brake disk is internally splined to the externally splined drag member 218 having a

conical bore receiving the conical member 202 for frictional engagement therewith. The brake disk 216 is similar in construction to the clutch disk 184 and hence includes a plurality of spring elements 220 which engage the spline disk member 218. The spring elements 220 and magnetic elements 214 when engaging the brake member 206 are thereby operative to yieldably bias the disk member 218 in a rearward direction as well as maintain the flux gap fixed prior to engagement without any need for adjustment. Accordingly, the bias imposed on the disk member 218 during engagement will permit slippage of the member 218 relative to the conical member 202 since it may be axially displaced forwardly along shaft 74 by a small amount limited by portion 198 of the clutch member 190. It will therefore be apparent, that power transmitted through the pulley 152 to the drive member 164 will be transmitted directly to the power shaft 74 through the slip clutch unit 173 when engaged while the brake device 204 applies a certain amount of drag to retard rotation when engaged. It will also be apparent, that slippage of the clutch member 190 occasioned by slight rearward axial movement relative to the conical member 194, and slippage of the drag member 218 occasioned by slight forward axial movement thereof relative to its conical member 202 will cause axial displacement of the respective members in opposite axial directions into engagement with each other. In this fashion, the assembly 172 will automatically vary the amount of power transmitted to the power shaft 74 from the drive member 164 and the amount of power absorbed in order to maintain a substantially constant torque on the driven spindle 30 to which the power shaft 74 is drivingly connected. The slip clutch and brake assembly 172 is particularly designed thereby, to accommodate the varying load applied to the spindle 30 in order to maintain a constant tension on the wire being wound. The magnetic force for alternatively holding the clutch unit 173 engaged and the brake unit 204 engaged may be produced by any suitable means the details of which form no part of the present invention, such as electromagnetic coil devices energized through suitable controls manufactured for example by Eaton Manufacturing Co. as Control Model B2C11-90 shown in its bulletin dated February 15, 1959 for the "Dyna-Torq" clutch and brake units. It should be appreciated therefore that the axial bias exerted by springs 192 and 220 on the clutch member 190 and drag member 218 respectively, is removed when the magnetic force is removed to disengage the clutch unit or the brake unit. The foregoing identified controls involve for example a two position switch which may be manually or automatically moved to a brake position to disengage the clutch unit and at the same time engage the brake unit in order to reduce torque transmitted to the power output spindle should there be an increase in tension and then moved to a clutch position for reengagement of the clutch unit and disengagement of the brake unit when wire tension decreases below some predetermined value. In view of the slippage involved, the slip clutch and brake assembly may be provided with facilities for removal of heat as for example the provision of cooling fins 222 on the slip clutch member 190.

60 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to falling within the scope of the invention as claimed.

What is claimed as new is as follows:

70 1. In a machine for respooling wire or the like on a spool, a drive mechanism for continuously rotating and cyclically reciprocating said spool to wind the wire thereon with substantially no variations in the tension of the wire comprising, a frame, an output spindle, means reciprocably mounting said spindle in said frame, a driven

power shaft rotatably mounted by said frame, variable speed ratio drive means drivingly connecting said power shaft to the spindle for continuous rotation thereof, reciprocating drive means drivingly connected to said power shaft, means operatively connecting said reciprocating drive means to the spindle for reciprocation thereof, a constant source of motive power, and power controlling means operatively connecting said constant source of motive power to the driven power shaft and responsive to variations in loading imposed thereon to correspondingly vary power continuously power transmitted to the power shaft from the constant source of motive power, said power controlling means including a slip clutch through which power is transmitted and a drag brake through which power is absorbed.

2. In a machine for re-spooling wire or the like on a spool, a drive mechanism for continuously rotating and cyclically reciprocating said spool to wind the wire thereon with substantially no variations in the tension of the wire comprising, a frame, an output spindle, means reciprocably mounting said spindle in said frame, a driven power shaft rotatably mounted by said frame, means drivingly connecting said power shaft to the spindle for continuous rotation thereof, reciprocating drive means drivingly connected to said power shaft, means operatively connecting said reciprocating drive means to the spindle for reciprocation thereof, a constant source of motive power, and power controlling means operatively connecting said constant source of motive power to the driven power shaft and responsive to variations in loading imposed thereon to correspondingly vary the power transmitted to the power shaft from the constant source of motive power, said power controlling means comprising, a drive member rotatably mounted on said power shaft, thrust means for holding said drive member axially fixed on said power shaft, a slip clutch member rotatably mounted on the power shaft, a stationary brake member, a driven member frictionally engaged with said slip clutch member, means slidably mounting said driven member on the power shaft for rotation therewith, coupling means rotatable with the drive member and engageable with the slip clutch member for transmitting torque thereto, means axially biasing the slip clutch member in one direction into engagement with the driven member when engaged with the coupling means to increase the torque transmitted to the power shaft, a drag member rotatable with the power shaft and axially engageable by the slip clutch member, brake engaging means mounted on the drag member and engageable with said stationary brake member, and second axial biasing means for axially biasing the drag member in said other direction to regulate absorption of torque when the brake engaging means is engaged with the stationary brake member, said axial biasing means comprise, magnetic means axially holding said coupling means and drag engaging means in engagement with the slip clutch and brake members, respectively, and spring means axially opposing the bias of the magnetic means to yieldably urge the slip clutch member and the drag member in opposite axial directions.

3. The combination of claim 2 wherein said reciprocating drive means comprises, a spirally grooved cam shaft rotatably mounted by the frame, a high reduction drive mechanism drivingly connecting the power shaft to the cam shaft, follower means engageable with said cam shaft for axial reciprocation therewith, a sleeve member mounted on the spindle in an axially fixed position, and lever means interconnecting said follower means with the sleeve member for imparting reciprocation thereto at an adjustable ratio to said reciprocation of the follower means.

4. The combination of claim 3 wherein said follower means comprises, a slide block having a bore through which said cam shaft extends, and a groove engaging element pivotally mounted within said block about a pivotal axis intersecting the cam shaft, said element hav-

ing an arcuate tooth projecting into the bore for engagement with the cam shaft, said tooth having a maximum thickness at the pivotal axis.

5. In combination with a driven power shaft, power controlling means comprising, a drive member rotatably mounted on said power shaft, thrust means for holding said drive member axially fixed on said power shaft, a slip clutch member rotatably mounted on the power shaft, a stationary brake member, a driven member frictionally engaged with said slip clutch member, means slidably mounting said driven member on the power shaft for rotation therewith, coupling means rotatable with the drive member and engageable with the slip clutch member for transmitting torque thereto, means axially biasing the slip clutch member in one direction into engagement with the driven member when the coupling means is engaged with the slip clutch member to increase the torque transmitted to the power shaft, drag brake means rotatable with the power shaft and axially engageable by the slip clutch member to absorb torque transmitted to the power shaft and means on the drag brake means engageable with said stationary brake member for axially biasing the drag brake means in said other direction to regulate absorption of torque.

6. A slip torque transmitting device comprising, a driven power shaft, a drive member rotatably mounted on said power shaft, thrust means for holding said drive member axially fixed on said power shaft, a slip clutch member rotatably mounted on the power shaft, a driven member frictionally engaged with said slip clutch member, means slidably mounting said driven member on the power shaft for rotation therewith, coupling means rotatable with the drive member and engageable with the slip clutch member for transmitting torque thereto, means axially biasing the slip clutch member in one direction into engagement with the driven member to increase the torque transmitted to the power shaft, said coupling means comprising a disk splined to the drive member, magnetic means axially holding said disk in engagement with the slip clutch member, and spring means axially opposing the bias of the magnetic means to yieldably urge the slip clutch member in said one direction when transmitting torque to the slip clutch member.

7. The combination of claim 1 wherein said reciprocating drive means comprises, a spirally grooved cam shaft rotatably mounted by the frame, a high reduction drive mechanism drivingly connecting the power shaft to the cam shaft, follower means engageable with said cam shaft for axial reciprocation therewith, a sleeve member mounted on the spindle in an axially fixed position, and lever means interconnecting said follower means with the sleeve member for imparting reciprocation thereto at an adjustable ratio to said reciprocation of the follower means.

8. The combination of claim 7 wherein said follower means comprises, a slide block having a bore through which said cam shaft extends, and a groove engaging element pivotally mounted within said block about a pivotal axis intersecting the cam shaft, said element having an arcuate tooth projecting into the bore for engagement with the cam shaft, said tooth having a maximum thickness at the pivotal axis.

9. In combination with a source of constant power and a driven member connected to a varying load, means for transmitting power to the driven member at a speed varied to maintain a constant torque comprising, a power transmitting shaft drivingly connected to the driven member, slip coupling means mounted on said shaft and drivingly connected to the source of constant power for transmitting power to the shaft, means biasing the slip coupling means in one direction when transmitting power for increasing the power transmitted therethrough, drag brake means mounted on said shaft for reducing the power transmitted to the driven member by the shaft, means biasing said drag brake means in the other direc-

tion when absorbing power for regulating the power absorbed, and means connected to the slip coupling means for axial engagement with the drag brake means.

10. A machine for re-spooling wire comprising a frame, an elongated spindle extending through said frame having a spool mounted on one end thereof, means mounting said spindle on the frame for rotation and axial reciprocation together with the spool, a power shaft rotatably mounted by the frame below the spindle, a drive motor drivingly connected to the power shaft, a slip clutch mounted on said power shaft including a drive member rotatably journaled on the power shaft in an axially fixed position, a conical driven member slidably splined to the power shaft, a torque transmitting member in frictional engagement with said driven member and coupling means splined to the drive member for yieldably holding the torque transmitting member in frictional engagement with the driven member while transmitting torque thereto, a camshaft rotatably mounted by the frame above the power shaft in parallel spaced relation to the spindle, means drivingly connecting the power shaft to the spindle at an end opposite said one end, means drivingly connecting the power shaft to the cam-

5 shaft at a selectively varied drive ratio, axial cam means mounted by the camshaft including spiral grooves formed therein and a reversing follower assembly slidably mounted thereon for reciprocating movement, a lever member pivotally connected to the follower assembly and the spindle, and stroke adjusting means pivotally mounting the lever member on the frame between said spindle and the camshaft.
